WOMAN'S HEAD SCARF

Gerald G. Burns, Rochester, N. Y.

Application June 1, 1949, Serial No. 2,988

Term of patent 14 years

(Cl. D3—12)

To all whom it may concern:

Be it known that I, Gerald G. Burns, a citizen of the United States, residing at Rochester, in the county of Monroe and State of New York, have invented a new, original, and ornamental Design for Woman's Head Scarf, of which the following is a specification, reference being had to the accompanying drawing, forming part thereof.

Fig. 1 is a view of a portion of a woman's head scarf on an enlarged scale, and

Fig. 2 is a view of the whole woman's head scarf, showing my new design.

I claim:

The ornamental design for a woman's head scarf, as shown.

GERALD G. BURNS.
